CLAIM

The ornamental design for a kayak roof rack, as shown and described.

DESCRIPTION

FIG. 1 is a perspective view of a kayak roof rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged detail view thereof, taken from area 8 in FIG. 2; and,

FIG. 9 is an enlarged detail view thereof, taken from area 9 in FIG. 4.

The broken lines illustrate boundary lines and lead lines depicting enlarged detail views and form no part of the claimed design.
